JAR CAP TOOL

Walter W. Harding, Martinsville, Ind.

Application September 2, 1937, Serial No. 162,216

9 Claims. (Cl. 81—15.1)

This invention relates to a tool for expanding and straightening jar caps.

Jar caps of the type used to seal preserving jars and the like can ordinarily be used only once due to the fact that they frequently become distorted and bent so that they will no longer clamp a sealing ring. This is usually in the form of bent flanges and caved in tops which prevent the caps from properly engaging the threaded end of the jar.

Tools have been devised to straighten the flanges, but no tool has been employed to expand the jar cap to its original dimension. This is important since a cap having part of its top caved in cannot clamp a sealing ring regardless of how straight the cap flange is, because the caved in portion will bind on the neck of the jar to prevent the cap being fully screwed on.

The object of this invention is to provide a tool whereby jar caps can be expanded and straightened after each use thereby allowing the caps to be used an unlimited number of times without danger of them failing to properly seal the contents.

Another object of the invention resides in providing a tool that will not damage the porcelain disk in the top of the cap when expanding it.

A further advantage of the invention is to provide a tool that will straighten the flange or expand the cap or both depending upon the condition of each individual cap.

Other objects and advantages of the invention will hereafter become more fully apparent from the following specification of which the drawing forms a part, and wherein:

Figure 1 is a top plan view of the invention;

Figure 2 is a side elevational view of the same;

Figure 3 is a vertical sectional view on the line 3—3 of Figure 1; and

Figure 4 is an enlarged vertical sectional view on the line 4—4 of Figure 1.

Referring more particularly to the drawing wherein like reference characters designate like or corresponding parts throughout the different views, 10 designates generally the tool which includes a ring 11 provided with a number of slots 12 which extend a part of the way around the ring 11 and are arranged at inclines. The ring 11 above the elevated end of each of the slots 12 is offset at 13 for a purpose which will hereafter be described.

Secured to the ring 11 is a handle 14 which may be of any desired shape or construction.

A disc or plate 15 is devised to fit into ring 11, and provided with ears 16 extending outwardly

from its periphery and adapted to be aligned with the offset portion 13, is intended to be inserted into ring 11 with ears 16 resting on the bottom wall of slot 12. To the under side of plate 15 is secured a disc 17 of smaller diameter than disc 15, which is held in position by the nuts and bolts 18. Disc 17 is provided with an annular depending flange 19 as best seen in Figure 4. A handle 20 having an offset portion 21 which engages the top of plate 15 and is secured thereto by the bolts 18, is adapted to be swung relatively to handle 14 to cause ears 16 to ride in slot 12 in a clockwise direction to force plate 15 downwardly with respect to ring 11. The same result can of course be obtained by operating handle 14 to move ring 11 in a counter clockwise direction relatively to plate 15 while it is being held stationary.

Extending inwardly from ring 11 is a flange 22, which is annular, and on which the flange of a metal jar cap 23 is adapted to rest to support the cap 23 in an inverted position in ring 11. The underside of plate 15 adjacent its periphery is beveled at 24 to engage the flange 25 of cap 23 as best seen in Figure 3.

As seen in Figure 4, ears 16 are directly beneath the offset portion 13 so that the beveled portion 24 is spaced from flange 22. As plate 15 is turned relatively to ring 11 ears 16 engaging slots 12 will guide plate 15 downwardly to clamp flange 25 between flange 22 and portion 24. If the flange 25 is at all distorted it will be straightened by this operation. The depending flange 19 will extend down into cap 23, and if the cap 23 is distorted as in Figure 3 the flange will be in engagement with the cap at the point 26.

As plate 15 moves downwardly therefore and the flange 25 is clamped between portions 22 and 24, the flange 19 at the point 26 will force the cap outwardly into expanded position, until the plate 15 reaches a fully lowered position. At such time the edge of flange 19 will be engaging cap 23 throughout the length of its periphery so that the dimensions of the cap will have been restored to its original condition.

Jar caps of the type shown at 23 are ordinarily provided with a porcelain insert 27, and for this reason flange 19 must be formed of a diameter sufficient to engage the cap at its extremities so that no pressure will be brought to bear against the porcelain disc 27 which would break it.

To remove the cap 23 after it has been restored to its original shape, plate 15 is turned counter clockwise until ears 16 reach the end of slot 12 directly beneath the offset portions 13, at which

time plate 15 can be lifted out of ring 11, and offset portions 13 will form a clearance to permit passage of the ears 16. The ring 11 can then be inverted so that cap 23 will drop out. Another cap 23 to be expanded and straightened can then be inserted in ring 11 after which plate 15 can be applied and the operation repeated.

From the foregoing it will be seen that the flange 19 simulates the neck of a jar, and tends 10 to expand the cap so that it will contact the edge of flange 19 at all points when plate 15 has been forced downwardly into a fully lowered position. It is therefore obvious that after a cap 23 has been subjected to the operation of tool 10, that 15 it will be in condition to engage firmly against the top of a jar neck. When in this condition a cap 23 is in condition to again be applied to a jar so that the flange 25 can securely clamp a rubber sealing ring so as to prevent air from entering the jar and spoiling the contents.

It is to be understood that the preferred embodiment of the invention only has been herein shown and described, the right being expressly reserved to make such changes and modifications 25 as will not depart from the spirit and scope of the invention.

I claim as my invention:

1. A metal cap expander comprising a ring provided with inclined slots, a handle secured to 30 said ring, a plate adapted to be inserted in said ring, said plate being provided with ears to engage said slots, a handle secured to said plate, means to support a metal cap in inverted position in said ring, and means depending from 35 said plate and extending into said cap to engage the inside thereof, said ring and plate adapted to be turned relatively to each other to cause said plate to move downwardly to press said cap into its original expanded shape.

2. A device of the class described comprising a ring provided with inclined slots, a plate adapted 40 to be inserted in said ring, said plate being provided with ears to engage said slots, said ring being provided with an annular inwardly extending flange to engage the flange of an inverted jar cap, said plate being beveled to engage 45 said cap flange, and operating means to turn said plate relatively to the ring to cause said ears and slots to cooperate to move said plate downwardly into clamping engagement with the cap flange to straighten it.

3. A jar cap straightener and expander comprising a ring provided with inclined slots, a plate sized to be inserted in said ring, said plate being provided with ears to engage said slots, a flange extending inwardly from said ring and adapted to support an inverted jar cap, said plate being provided with a depending flange member to extend into the cap, said ears and slots co- 55 operating to force said plate downwardly when turned relatively to said ring to cause said de-

pendent flange to press the cap outwardly into its original expanded shape.

4. A jar cap tool comprising a ring having inclined slots, a plate adapted to be inserted in said ring and provided with ears to engage said slots, a flange secured to said ring to support a cap in inverted position, an annular flange depending from said plate and adapted to extend into said cap, and operating means to turn said ring and plate relatively to each other to cause 10 said ears to move in said slots to force said plate downwardly, and its depending flange into engagement with said cap to press it out into its original expanded condition.

5. A device as in claim 4 and the under part 15 of said plate cooperating with the flange on said ring to bend the jar cap flange outwardly into a uniform shape.

6. A tool for expanding and straightening jar caps comprising a ring provided with a plurality 20 of inclined slots, a plate sized to fit into said ring and provided with ears to engage said slots, said ring being provided with offset portions adjacent the top of each slot to admit said ears, means to clamp a jar top between said ring and plate, an annular flange depending from said plate and extending into said cap, and operating means to turn said plate and ring to cause said ears to move in said slots to force said plate downwardly whereby to simultaneously clamp 30 and straighten the cap flange and expand the cap due to the downward pressure of the annular depending flange.

7. In a cap expander, a pair of connected members, one of said members being adapted to receive a jar cap, means for turning said members relatively to each other, means connecting said members whereby they will be moved longitudinally of each other by said turning movement, and a portion projecting from the other of said 40 members to engage the cap to bend it back into its normal shape.

8. A jar cap tool comprising a ring provided with a handle, a member mounted in said ring and having a handle, said ring and member 45 being rotatable relatively to each other and adapted to receive a jar cap, and means connecting said members whereby they will be moved longitudinally, relatively to each other, as they are revolved to clamp and expand the 50 jar cap.

9. In a jar cap tool, a ring having means to support a jar cap therein, a disc removably mounted in said ring, and means formed in said ring to engage means on said disc for rotatably 55 mounting the ring and disc relatively to each other to clamp and straighten the flange of the cap, and means on said disc to simultaneously expand the cap into its original shape as the flange is clamped and straightened.

WALTER W. HARDING.
